United States Patent

Des. 240,257
Patented June 8, 1976

240,257

PENDANT OR SIMILAR ARTICLE

Margaretta C. Roberts, Providence, R.I., assignor to Reed & Barton Corporation, Taunton, Mass.

Filed May 23, 1974, Ser. No. 472,834

Term of patent 3½ years

Int. Cl. D11—01

U.S. Cl. D45—19 S

FIG. 1

FIG. 2

FIG. 3

FIG. 4

FIG. 5

FIG. 1 is a front elevational view of a pendant or similar article showing my new design;
FIG. 2 is a rear elevational view thereof;
FIG. 3 is a right side elevational view thereof;
FIG. 4 is a top plan view thereof; and
FIG. 5 is a bottom plan view thereof.

I claim:

The ornamental design for a pendant or similar article substantially as shown.
